FEEDING MECHANISM.

Application filed October 24, 1925. Serial No. 64,586.

- This invention relates to an improved sheet feeding mechanism for use in connection with printing presses, folding machines and the like.
- 5 The principal object of the invention is to provide a feeder of the pneumatic or suction type which automatically adapts itself to varying grades or thicknesses of sheets to be fed. In this connection it is the aim 10 of the invention to eliminate the necessity of adjusting the feed mechanism for each and every grade of paper stock, as is required at the present time, and to provide feeding mechanism which will separate and 15 feed relatively thick as well as thin paper stock without necessitating a change in the vacuum or of any adjustment whatsoever.
- A further object is to accomplish the above with mechanism which is simple in 20 construction, and efficient and reliable in action.
- The invention may be briefly summarized as consisting in certain novel combinations and arrangements of parts, and details of 25 construction which will be described in the specification and set forth in the appended claims.
- In the accompanying sheets of drawings wherein I have illustrated an embodiment 30 which operates with high efficiency, Fig. 1 is a side elevation of a portion of a flat bed printing press equipped with my invention, a portion of the press only being shown; Fig. 2 is a view on a slightly larger scale, 35 looking at the opposite side of the machine from that shown in Fig. 1, and shows the feeding end only; Fig. 2^a is a fragmentary plan view showing certain parts of the pile-height gauge; Fig. 3 is a longitudinal sectional view showing particularly the feeding mechanism; Fig. 4 is a top plan view of the feeding mechanism; Fig. 5 is a detail perspective view showing certain parts instrumental in the feed of the paper stock; Fig. 40 6 is a detail sectional view substantially along the irregular line 6—6 of Fig. 4; and Fig. 7 is a detail of a mechanically operated valve which automatically interrupts the suction at the feeding end during the return 45 stroke of the oscillating perforated feeder.
- Referring now to the drawings, 10 represents the frame of the machine in connection with which the feeding mechanism is used, and which as here shown is a printing press. As the invention does not involve 55 any details of the press, and, in fact, as it may be used advantageously with other types of machines, such as folding machines, it is unnecessary to describe the press itself.
- The feeding mechanism is supported on a 60 suitable frame 11, which may be attached to or form a part of the frame 10.
- The paper stock is fed from a pile 12, indicated in Fig. 3, and supported on an automatically elevated platform 13, guided for 65 vertical movement on rods 14 forming a part of the frame 11. The function of the mechanism forming the principal part of the present invention is to elevate the top sheet from the pile 12 until it engages on the under side 70 of a so-called separator plate 15 extending horizontally between the side members of the frame 11, and then to feed the sheet forwardly between take-off rolls 16 and traveling tapes 17 designed to carry the sheets one 75 at a time into the press or other machine. The take-off rolls 16 are periodically moved up and down, being elevated to permit a sheet to be fed forwardly beneath them, and being lowered into contact with the tapes 80 17 so as to be fed down into the press or other machine. The rolls 16 are carried by levers 18 pivoted between their ends on a 85 stationary horizontal shaft, and the rear ends of the levers have rollers 20 adapted to engage cams 21 on a power driven shaft 22.
- The tapes 17 are driven by a power driven shaft 20^a, which it will be observed by reference to Fig. 2, is driven by gears 23 and 24, the latter being on a stud supported by 90 the frame 11 and driven by chain and sprocket gearing 25 from shaft 22, the latter being the main power shaft of the feeding mechanism. By reference to Fig. 1 it will be seen that this shaft is driven by bevel 95 gears and shafts designated as a whole by the reference character 26 and extending down and rearwardly along the main frame 10, and in turn driven by a shaft 27 constituting the main drive shaft of the machine. 100

As before stated, the paper stock is in the pile 12, supported on the platform 13, which is elevated at intervals to maintain substantially a fixed or constant distance 5 between the uppermost sheet of the pile and the horizontal separator plate 15. This platform is supported by sprocket chains 28 which pass over sprockets 29 on a shaft 30 extending between the side plates of the 10 frame 11, forwardly and somewhat above the main feed shaft 22. On this shaft is a ratchet 31 (see Fig. 2), held from reverse rotation by a holding pawl 32, and adapted to be given a step by step movement in a 15 clockwise direction as viewed in Fig. 2 so as to elevate the platform 13 by a pawl 33 carried by an arm 34 mounted to swing freely on the shaft 30, and connected by a link 35 to a lever 36 mounted on the frame 20 11 and in turn connected by a link 37 to a lever 38 pivoted at 39 on the frame 11 and at its upper end having a slot which is engaged by a crank pin 40 of a crank disk 41 mounted on the main feed shaft 22. As 25 the shaft 22 is rotated constantly, the lever 38, and consequently the arm 34 are rocked back and forth at a uniform rate, causing the ratchet 31 to be stepped up and the elevator shaft 30 to be turned, providing pawl 33 is permitted to engage the teeth of ratchet 31.

Normally the pawl 33 is out of engagement with the ratchet 31, and the engagement and disengagement is controlled by a pile-height 35 gauge which includes a roller 42 which is adapted to engage the top sheet of the pile, as indicated in Fig. 3, this roller being supported on the forward end of a finger 43, 40 adjustably secured in a block 44 which is adjustably fixed to a rock shaft 45 extending across the forwardmost ends of the side plates of frame 11. The rock shaft 45 is provided at one end with a collar 46 (see Fig. 2), to which is attached a rod 47 which 45 engages under a finger 48 extending laterally from pawl 33.

It is not desirable that the roller 42 rest on the top of the pile 12 during the forward strokes of the oscillating feeder, to be referred to presently, as it would cause too great a resistance to the feed of the sheets, and therefore it is preferable that the roller be lifted from the pile on and during the active strokes of the feeders and allowed to 55 drop down onto and to rest on the pile during the idle or return strokes of the feeders, and at such times perform its gauging function. To lift the roller from the pile on each active stroke of the feeders I pivotally 60 connect to the upper end of the pitman 36 at the point 36^a where the pitman is connected to the link 35, an arm 36^b which has a back and forth movement as the pitman is oscillated. The arm has a slot 36^c through 65 which the rod 47 passes, as illustrated in

Figs. 2 and 2^a, the action being such that on the forward stroke of the feeders the arm 36^b is moved rearwardly, and when the end of the slot reaches the rod 47, the latter is swung upward just enough to lift the roller 70 75 from the top of the pile and permit the topmost sheet to be fed therefrom without being restrained by the weight of the roller. When the pitman 36 swings forwardly or in the opposite direction, as it does during the 75 return or idle stroke of the feeders, the slot 36^c permits the rod 47 to move downward until the roller again engages the top of the pile.

The action of the pile-height gauge is as follows: When the top of the pile is not less than a certain distance (in practice about one-eighth of an inch) from the separator plate 15, the positions of the roller 42, finger 43 and rod 47 are such as to hold the pawl 80 33 out of engagement with the teeth of the ratchet 31, in which event the pitman 34 carrying the pawl makes idle strokes, but as the stock is fed from the top of the pile, the roller 42 of course moves downward, and 90 when the top sheet is a predetermined maximum distance from the separator plate, the lowering of the roller 42 has become such as to permit the pawl 33 to operatively engage ratchet 31, in which event the sprockets 95 29 and shaft 30 are turned so as to elevate the elevator 13 and pile 12 one step, whereupon the pawl 33 is again disengaged from the ratchet 31 and remains disengaged until the 100 top sheet of the pile 12 again reaches the maximum distance from the separator plate when the elevating operation is repeated.

Coming now more directly to the pneumatic feeding mechanism, the latter involves pneumatic means for separating the top 105 sheet from the pile and for elevating it against the lower side of the separator plate 15, and pneumatic means for then feeding the sheet forwardly a distance sufficient to cause it to be grasped between the take-off 110 rolls 16 and the tapes 17, the rolls being frictionally driven by the tapes. For the purpose of separating the top sheet from the pile, a blast of air is directed against the front edge of the top sheet, its force being 115 sufficient to elevate the sheet against the separator plate, but suction is utilized in holding the top sheet thus elevated against the feeder proper, which it may be here stated is oscillated back and forth.

For the purpose of creating the draft of air which elevates the top sheet of the pile, and for the purpose of creating the suction necessary in feeding the sheet, a rotary pump 49 is utilized (see Fig. 1), the same being 125 suitably driven from the main power shaft 27 of the machine. This pump has an intake or suction pipe 51 and an outlet or delivery pipe 52, both connected to its casing. The delivery pipe 52 extends laterally along the 130

frame 10 and up along the frame 11, as indicated in Fig. 1, and up along the front of the pile 12, as best indicated in Fig. 6. Telescopically engaging in the upper end of the pipe 52 directly in front of the pile 12 is a so-called blow pipe 53 with a delivery opening facing rearwardly and so positioned as to constantly direct a stream of air against the front edge of the top sheet so as to elevate the latter immediately after a sheet is fed forwardly into the press or other machine. The blow pipe 53 is adjustable vertically, having a rack arm 54 attached to it and adapted to be engaged by an adjusting wheel 55 indicated in Fig. 6. When once the position of the separating jet is determined, the blow pipe need not be adjusted, as the proper height of the top of the pile is maintained by the elevating mechanism already described.

For the purpose of feeding the sheets one at a time from the top of the pile as they are severally elevated in the manner explained below, I employ one or more oscillating feeders 56, which involve very important features of my invention. These feeders are segment shaped, and are mounted for oscillatory movement on the stationary shaft 19, previously referred to, and they are oscillated or rocked back and forth by a crank 57 connected to a pair of crank disks 58 on the main driving shaft 22 of the feeding mechanism (see particularly Fig. 4). Each oscillating feeder 56 is provided with a laterally projecting flange 57 which extends down into the opening 15^b of the separator plate, the lower face of the flange being slightly below the lower side of the separator plate so that the elevated sheet of paper at the top of the pile 12 and the feeder may have effective engagement under the action of suction or vacuum acting through the flange 57 of the feeder to move the sheet forwardly to a position such that it may be engaged between the take-off rolls 16 and the feeding tapes 17, these rolls being lowered by the action of the cams 21 on the rollers 20, as the sheet is fed forwardly.

It will be observed that the flange 57 is provided with a series of radially disposed openings 58 extending therethrough, which openings are of graduated or varying sizes, the diameter of the openings gradually increasing from the forwardmost to the last or endmost.

Engaging the arc shaped top surface of the flange 57 of each feeder is a stationary suction block 59, mounted in fixed position on the stationary shaft 19 (see particularly Figs. 5 and 6). Each suction block 59 has an opening 60 extending up a suitable distance from its lower end and communicating with the upper end of the opening is a suction or vacuum tube 61, which as will be explained, is in communication with the pump 49. The

lower end of the opening 60 is successively placed in communication with the openings 58 extending through the flange of the oscillating feeder 56, so that the suction or partial vacuum created in tube 61 and opening 60 of the suction block will be exerted on the elevated topmost sheet of the pile through the openings 58, as they successively pass beneath and in registration with the opening 60 of the stationary suction block.

It was previously stated that one or more oscillating suction feeders are employed. It will be understood, of course, that for each such oscillating feeder there will be associated a stationary suction block in the relationship shown in Fig. 5. In some instances a single oscillating feeder and stationary suction block may be employed to feed the sheets from the pile 12, but generally at least two such feeders and associated suction blocks will be employed, and two are shown in the drawings, as clearly illustrated in Fig. 4. For exceptionally wide sheets there may be more than two feeders.

Considering now the mechanism by which a suction or vacuum effect is created in the openings of the suction blocks 59 and the tubes 61 connected thereto, reference will first be had to Fig. 1. It will be observed that the suction or intake pipe 51 connected to the pump 49 is connected to a vacuum tank 62 in which a predetermined vacuum is maintained, the degree of vacuum depending generally upon the speed of the pump 49. Extending from the vacuum tank 62 is a pipe 63 connected to a tube 64, and between the pipe and tube is any suitable vacuum reducing valve 65 which can be adjusted so as to cause any desired degree of vacuum to be created in tube 64 less than that in vacuum tank 62. As vacuum reducing valves are well-known, I have not deemed it essential to show the details of the valve, but in the present instance the reduction in degree of vacuum between that in tank 62 and that in tube 64 is controlled by a spring 65^a, the tension of which can be adjusted by a nut 65^b on the valve stem 65^c extending up from the reducing valve 65.

The tube 64 extends up to a shut-off valve 66, to the casing or chamber of which are connected the tubes 61, which in the manner illustrated in Figs. 4 and 5, are connected to the suction blocks 59 of the oscillating feeders. The function of this valve is to shut off or relieve the suction or vacuum in the tubes 61 and suction blocks 59 on the back stroke of the oscillating feeders 56, so that when the feeders are swinging rearwardly they will have no effect on the elevated sheet at the top of the pile, and to establish the suction or vacuum in tube 61 during the forward stroke of the feeders. This valve may assume different forms, but in this instance, and as shown in

Fig. 7, it includes an elongated casing 66^a adapted to be traversed by a plunger 66^b, which is moved outwardly by a spring 66^c, and is pressed inwardly by the engagement 5 of a roller 66^d by a cam 67 on one of the shafts 26 driving the main shaft 22 of the feeder (see particularly Fig. 1). The casing 66^a has a port 66^e, to which the tube 64 is connected, and adjacent the end there are 10 two ports 66^f, to which the tubes 61 are connected. The construction is such that when the spring moves the plunger to the position shown in Fig. 7, or to the right as viewed in this figure, communication is established be- 15 tween port 66^e and the ports 66^f, causing the suction or vacuum to be created in the tubes 61, but when the plunger is moved inward by the cam 67, port 66^e is closed by the plunger and the end of the chamber or casing of the 20 valve is opened at 66^f, placing the ports 66^f in communication with the atmosphere and instantly relieving the vacuum or suction in tubes 61.

The action of the feeder is as follows: A 25 pile of paper stock is placed on the platform and lined up in front in the proper position against a pair of guide rods 68, one of which is shown in Fig. 3, and both being indicated in Fig. 4, these guide rods engaging the front 30 of the pile on opposite sides of the blow pipe 53. When the machine is in operation, the oscillating feeders 56 swing back and forth, the graduated openings 58 of each being successively brought into registration with the 35 opening 60 of the suction block 59. The jet of air being constantly directed by the blow pipe against the front edge of the top sheet elevates the latter as soon as a sheet is fed into the machine, and on each forward 40 stroke of the feeders suction is exerted on the sheet through the openings 58, and when an opening 58 of proper size comes into 45 registration with the opening 60 of the suction block to exert a sufficient suctional force on the sheet to overcome its inertia and frictional resistance to movement, the sheet will be moved forward, and on or about the end of the forward movement of the oscillating feeders the take-off rolls are lowered onto 50 the sheet, causing it to be fed into the press or other machine. On the return stroke of the feeders no suction is exerted on the sheet since during this period the vacuum or suction tubes 61 are open to atmosphere at the 55 valve 66.

The feeders swing back and forth at high speed, causing suction to be exerted on the sheet on each forward stroke and feeding one sheet at each forward stroke, but swinging 60 freely without suction on the return stroke.

By reason of the fact that the feeders have a series of graduated openings, stock of varying thickness and weight can be fed without making any adjustment in the feeding 65 mechanism, for the feeder will move for-

wardly until an opening of sufficient size is presented to the opening in the suction block to feed the sheet. For a sheet of light weight, the first, or one of the foremost openings may be sufficiently large to permit the necessary suctional force to be exerted on the sheet to cause it to be moved. On the other hand, if a sheet is relatively heavy, a later or larger opening will eventually come into registration with the opening 60 of the suction block to permit the necessary suctional force to be exerted on the sheet to move it forwardly. Any slight irregularity in the feed of the sheets, due to the fact that in feeding successive sheets different openings of the feeder may become effective to feed them, if the sheets are of varying thickness and weight, is absolutely of no consequence for the reason that the sheets are stopped or held momentarily at the lower ends of the tapes before being fed into the machine. The feature of having the graduated openings in the oscillating feeders is of importance when the sheets in the pile by accident or otherwise are not of uniform thickness, but its chief importance lies in the fact that the feeder can be utilized for feeding piles of thin sheets and thick sheets, and, in fact, sheets of any thickness and size (within limits) without requiring any change or adjustment of the feeding mechanism, whereas heretofore it has been necessary to have in stock a series of nozzles which had to be changed as the size of the stock varied, and often requiring the exercise of considerable skill on the part of the operator in changing over the machine by the selection of the proper nozzle or otherwise, as by adjusting vacuum valves and the like, all of which are avoided by my improvements.

Having described my invention, I claim:

1. A feeding mechanism comprising a movable feeder member movable over the sheet to be fed, and means for creating a suction through the feeder member onto the sheet, said feeder having means whereby the suctional force exerted on the sheet is varied during substantially the entire feeding movement of the feeder member.

2. A feeding mechanism for feeding sheets from a pile comprising a movable feeder adapted to be engaged by the top-most sheet of the pile to cause a suctional force to be exerted on the sheet, and suction means connected to the feeder, said feeder having means whereby the force exerted on the sheet is gradually increased as the feeder moves over the sheet during substantially the entire feeding movement.

3. A feeding mechanism for feeding sheets from the top of a pile comprising a sheet elevating means and a movable feeder which during substantially the entire feeding movement exerts a gradually increasing

- suctional force on the topmost sheet, and suction means connected to the feeder.
4. A feeding mechanism for feeding sheets from the top of a pile comprising a pneumatic sheet elevator and a movable pneumatic sheet feeder which exerts a gradually increasing suctional force on the topmost sheet during substantially the entire feeding movement.
5. A feeding mechanism for feeding sheets from the top of a pile comprising an oscillating feeder through which a suctional force is exerted on the topmost sheet, suction means connected with the oscillating feeder and means for swinging said feeder back and forth about a stationary axis.
6. A feeding mechanism for feeding sheets from the top of a pile comprising a member movable back and forth and having a series of openings through which a suctional force is adapted to be exerted, a stationary member having an opening with which said first-named openings are adapted to register successively and means for moving said member forwardly to feed a sheet and then back through the same path.
7. A feeding mechanism for feeding sheets from a pile comprising a movable feeder member having openings of varying sizes through which a suctional force is adapted to be exerted on a sheet.
8. A feeding mechanism comprising a movable feeder member, means for moving it back and forth, the return movement being through the same path as the forward movement, said feeder member having spaced openings through which a suctional force is adapted to be exerted on a sheet, and suction means including a part having an opening adapted to register successively with the different openings of the feeder member.
9. A feeding mechanism for feeding sheets from the top of a pile comprising a movable feeder member, means for moving it back and forth, said member having a plurality of openings of varying sizes, and suction means including a part engaging said feeder member so that suction is exerted successively through the different openings.
10. A feeding mechanism for feeding sheets from the top of a pile comprising a pivoted feeder member, means for swinging it back and forth, said member having a plurality of openings of gradually varying sizes, and a suction block engaging the feeder member and having an opening which registers successively with the different openings of the feeder member.
11. A feeding mechanism for feeding sheets from the top of a pile comprising a movable feeder member, pneumatic means for elevating the topmost sheet of the pile into engagement therewith, said feeder member having a series of openings of graduated sizes and a suction block engaging said feeder member and having an opening which registers successively with the different openings of the feeder member, and means for moving said feeder member back and forth.
12. A feeding mechanism for feeding sheets from the top of a pile comprising a movable feeder member, pneumatic means for elevating the topmost sheet of the pile into engagement therewith, said feeder member having a series of openings of graduated sizes and a suction block engaging said feeder member and having an opening which registers successively with the different openings of the feeder member, and means for oscillating the feeder member.
13. In a feeding mechanism for feeding sheets from the top of a pile, a feeder member movable back and forth, the return movement being through the same path as the forward movement, and having a plurality of openings through which a suctional force is adapted to be exerted on the topmost sheet, suction means operatively connected to the feeder member, means for alternately moving said feeder member forwardly and rearwardly, and means for causing the suction means to be rendered ineffective during the rearward movements of the feeder member.
14. In a sheet feeding mechanism, a feeder member movable back and forth and having a plurality of openings of graduated sizes through which a suctional force is adapted to be exerted on a sheet, suction means including a part engaging the feeder member and adapted to cause the suction to be exerted successively through the different openings, and means for causing the suction means to be rendered ineffective when the feeder member is moving in one direction and effective when it is moving in the opposite direction.
15. In a sheet feeding mechanism, an oscillatory feeder member, means for actuating the same so as to give it alternately a forward feeding movement and a return movement, suction means operatively connected with the feeder member about a stationary axis, and means for rendering the suction means ineffective during the return stroke of the feeder member.
16. A sheet feeding mechanism comprising an oscillatory feeder member having a plurality of openings through which a suctional force is adapted to be exerted on the sheet to be moved, means for actuating said feeder member so as to give it alternate feeding and return strokes about a fixed axis, means including a part operatively connected to the feeder so that suctional force is successively exerted on the sheet through the different openings, and means for rendering the suction means ineffective during each return stroke of the feeder member.

- 6
17. A feeding mechanism comprising an oscillatory feeder member having an arc-shaped portion provided with spaced openings of different sizes, a suction block engaging said portion and having an opening adapted to register successively with the different openings of the feeder member, such tion means connected with said block and means for rendering said suction means ineffective during each return stroke of the 10 feeder member.

In testimony whereof, I hereunto affix my signature.

CLARENCE E. McKINSEY.
